UNITED STATES PATENT OFFICE.

GEORGE HENRY WHEARY, OF RACINE, WISCONSIN.

WARDROBE-TRUNK.

1,317,188.

Specification of Letters Patent. Patented Sept. 30, 1919.

Application filed August 2, 1918. Serial No. 247,935.

To all whom it may concern:

Be it known that I, GEORGE HENRY WHEARY, a citizen of the United States, and resident of Racine, in the county of Racine and State of Wisconsin, have invented new and useful Improvements in Wardrobe-Trunks, of which the following is a description, reference being had to the accompanying drawings, which are a part of this specification.

This invention relates to improvements in wardrobe trunks.

Wardrobe trunks of the better class are usually divided vertically into two parts to form a wardrobe section and a drawer section. The two parts are hinged together to swing horizontally to open or closed position, and the wardrobe section is provided with garment hangers for suspending outer wearing apparel thereon, and the other section is provided with drawers for holding underwear and other articles of wear.

Trunks of this type are usually formed of wood covered with fiber, and the fiber at the abutting edges of the sections is usually folded inwardly over the section edges to form a finish, and the inner portions of the sections are usually lined with a suitable fabric to finish the interior edges of the fiber.

In trunks of this type it is necessary to provide means for holding the drawers in position and prevent them from working into the wardrobe section. It is also necessary to provide means for mounting a shoe box within the wardrobe section.

The interior linings for the trunk sections are expensive and not as sanitary as may be desired. Furthermore, the drawer and shoe box holding means are also expensive to attach to the trunk sections, and materially increase the cost of same.

It is one of the objects of the present invention to provide a wardrobe trunk having an improved form of valance which forms a finish for the edges of the trunk sections and thereby eliminates the use of interior linings.

A further object of the invention is to provide a wardrobe trunk having an improved form of valance which forms a dust proof joint between the two trunk sections and also serves to reinforce the edges thereof.

A further object of the invention is to provide a wardrobe trunk having an improved form of valance which is adapted to hold the

drawer in closed position when the trunk sections are in closed position.

A further object of the invention is to provide a wardrobe trunk having an improved form of valance which permits the easy attachment of a show box thereto.

A further object of the invention is to provide a wardrobe trunk which is of simple construction, is strong and durable, and is well adapted for the purpose described.

With the above and other objects in view the invention consists of the improved wardrobe trunk and its parts and combinations as set forth in the claims, and all equivalents thereof.

In the accompanying drawings in which the same reference characters indicate the same parts in all of the views:

Figure 1 is a front view of the improved wardrobe trunk shown in open position;

Fig. 2 is a transverse sectional view thereof in folded position taken on line 2—2 of Fig. 1;

Fig. 3 is a transverse sectional detail view, on a larger scale, of parts shown in Fig. 2;

Fig. 4 is a vertical sectional detail view of a part of the top cover and side portion of the trunk;

Fig. 5 is a similar view of the joint formed between the top cover and the upper portion of the drawer section of the trunk; and

Fig. 6 is a vertical sectional detail view taken on line 6—6 of Fig. 1.

Referring to the drawings the numeral 8 indicates the wardrobe section, and 9 the drawer section of the improved trunk. The two sections are hinged together to swing horizontally to closed or open position, and the wardrobe section is provided with a hinged top cover 10 for convenient access to garments which may be suspended from hangers 11 slidably mounted within said wardrobe section. Said wardrobe section is also provided with a removable garment retainer 12 and a shoe box 13, and the drawer section is provided with a plurality of drawers 14.

The principal feature of the invention is the novel shape of the coacting valance members whereby many desirable advantages are obtained.

The valance members 15 mounted on the side portions 16 of the wardrobe section are preferably formed of a strip of metal folded over medially of its width to form an in-

turned drawer stop or holding flange 17 of double thickness and then both side portions 18 and 18' are bent at right angles to the stop flange and in spaced relation to form an 5 elongated groove 19 to receive the forward edges of the side portions 16, as clearly shown in Fig. 3. The side portion 18 is slightly offset, as indicated by the numeral 20 to accommodate the outer fiber covering 10 21 of the trunk, and to form approximately a flush surface with the flange of the coating valance member which will later be described.

The valance members 22 of the upper and 15 lower front edges of the wardrobe section are similar to the members 15, with the exception that the stop flange 17 is omitted, and the same reference numerals will apply.

20 The coating valance member 23 of the drawer section of the trunk is the same on all side, top and bottom edges and comprises preferably a strip of metal folded over medially of its width to form an over- 25 lapping flange portion 24 of double thickness which overlaps the outer side portions of the valance member 15. The inner side portion of the member 15 is bent inwardly at right angles to form the rabbeted end 30 25 of the member, and the side portion is again bent at right angles to the rabbeted end to form an elongated groove 26 to receive the forward edges of the side, top and bottom walls of the drawer section, 9, 35 as clearly shown in Figs. 2, 3 and 5.

When the two trunk sections are in closed position, the flat end portions of the coating valance member will form the abutting end portions of the trunk sections, and the 40 flanges 24 will overlap the outer portion of the member 15 to the line of offset indicated by the numeral 20. When thus in closed position, the stop flanges 17 will extend inwardly beyond the inner surfaces of the inner walls of the trunk sections and in front of the drawers of the drawer section, and thus hold said drawers in closed position as shown in Fig. 2.

The side edge portions of the top cover 50 10 are also provided with valance members 27 which coat with valance members 28 mounted on the upper side edges of the wardrobe section 8. Each valance member 27 comprises preferably a strip of metal folded over medially of its width to form a downwardly extending overlapping flange portion 29 of double thickness which overlaps the outer side of each side member 28. The opposite side portions 30 of said 55 member 27 are bent at right angles with relation to the folded part and in spaced relation to form an elongated groove 31 to receive the opposite side edges of the top cover 10. The valance members 28 are 60 formed of preferably strips of material 65

bent U-shape to form elongated grooves 32 for receiving the upper edges of the side walls 16 of the wardrobe section. The outer side portions of said members 28 are offset outwardly as indicated by the numeral 33 70 to accommodate the outer fiber covering 21 and to form approximately a flush outer surface with the overlapping flange 29.

The stop flange at the lower portion of the trunk section is provided with recesses 75 34 and 35 for receiving respectively the lower pivot trunnions 36 and the stop fingers 37 of the shoe box 13. Said shoe box is also provided with spring latches 38 which bear against the inner side of the stop flange 80 17 to removably lock the shoe box in position.

The coating valance members form dust proof joints and greatly reinforce the edge portions of the open sides of the trunk sections and also provide a convenient construction for attaching a shoe box thereto. 85

From the foregoing description it will be seen that the wardrobe trunk is of very simple construction and is well adapted for 90 the purpose described.

What I claim as my invention is:

1. A wardrobe trunk, comprising trunk sections having adjacent edge portions, and coating valance members mounted on said edge portions, one of said valance members consisting of a strip of material shaped to form a groove to receive the edge portion of one of the trunk sections and to form an in-turned drawer stop flange which extends at 100 right angles from the trunk section, the other valance member consisting of a strip of material shaped to form a groove to receive the edge portions of the other trunk section and to also form a rabbet joint with the other valance member. 105

2. A wardrobe trunk, comprising trunk sections having adjacent edge portions, and coating valance members mounted on said edge portions, one of said valance members consisting of a strip of material folded medially of its width to form an elongated groove to receive the edge portion of one of the trunk sections and to form an in-turned drawer stop flange which projects 115 inwardly at right angles from and beyond the inner surfaces of the side walls of the trunk section, the other valance member consisting of a strip of material folded medially of its width to form an elongated groove to receive the edge portion of the other trunk section and to also form a projecting flange which will overlap side portions of the other valance members when the trunk sections are in folded position. 120

3. A wardrobe trunk, comprising hinged together trunk sections having adjacent edge portions, and coating valance members mounted on said edge portions, one of said valance members consisting of a 125

strip of material folded over in part upon itself medially of its width to form an elongated groove to receive the edge portion of one of the trunk sections 5 and to form an inturned drawer stop flange of double thickness which projects inwardly beyond the inner surfaces of the side walls of the trunk section, the other valance member consisting of a strip of material folded 10 over in part upon itself medially of its width to form an elongated groove to receive the edge portion of the other trunk section, and to also form a projecting flange of double thickness which will overlap the 15 side portions of the other valance member when the trunk sections are in folded position.

4. A wardrobe trunk, comprising hinged together trunk sections having adjacent 20 edge portions, drawers mounted in one of the trunk sections, and coacting valance members mounted on the edge portions of said trunk sections, one of said valance members consisting of a strip of 25 material folded over in part upon itself medially of its width to form an elongated groove to receive the edge portions of one of the trunk sections and to also form an inturned stop flange which bears against 30 and holds the drawers of the other trunk section in closed position when said trunk sections are in closed position, the other valance member consisting of a strip of material folded over in part upon itself medially of its width to form an elongated 35 groove to receive the edge portion of the drawer trunk section and to also form a projecting flange which will overlap the side portions of the other valance member when 40 the trunk sections are in closed positions.

5. A valance joint for a trunk, comprising a pair of coacting valance members, one of 45 said members consisting of a strip of material folded over in part upon itself medially of its width to form an elongated groove and an inturned drawer stop member extending at right angles from the other portion, the other valance member consisting of a strip of material folded over in 50 part upon itself medially of its width to form an elongated groove and a projecting flange which will overlap the side portions of the other valance member.

6. A valance joint for a trunk, comprising 55 a pair of coacting valance members, one of said members consisting of a strip of material folded over in part upon itself medially of its width to form a drawer stop portion and then both side portions extending in spaced relation at right angles to the stop portion to form an elongated groove, the other valance member consisting of a strip of material folded over in part upon itself medially of its width to form an overlapping portion and then extending at right 65

angles to the overlapping portion and again extending at right angles thereto to form an elongated groove.

7. A valance joint member for a trunk, consisting of a strip of material folded over 70 in part upon itself medially of its width to form a drawer stop portion and then both side portions extending in spaced relation and at right angles to the stop portion to form an elongated groove. 75

8. A valance joint member for a trunk, consisting of a strip of material folded over in part upon itself medially of its width to form an overlapping portion and then extending at right angles to the overlapping 80 portion, and again extending at right angles thereto to form an elongated groove.

9. A valance joint for a trunk, comprising a pair of abutting grooved and flanged members, the flange of one member extending approximately at right angles to the flange of the other member to form a drawer 85 stop.

10. A valance joint for a trunk, comprising a pair of abutting grooved and flanged 90 members, the flange of one member overlapping the outer side of the other member and the flange of said other member extending inwardly approximately at right angles to and beyond the flange of the other 95 member to form a drawer stop.

11. A wardrobe trunk, comprising hinged together trunk sections having adjacent edge portions, one of said sections having a hinged top cover, and coacting valance 100 members mounted on the edge and top cover portions, one of said valance members consisting of a strip of metal folded over in part upon itself medially of its width to form overlapping portions, and then extending at right angles to form grooves for receiving edge portions of the trunk, another of said valance members consisting of a strip of metal folded over in part upon itself medially of its width to form a drawer 105 holding portion and then both side portions extending in spaced relation and at right angles to the stop portion to form an elongated groove for receiving edge portions of the trunk, and another of said valance members formed of a strip of metal folded over 110 medially of its width to form a downwardly extending overlapping flange having side portions extending at right angles in spaced relation to form an elongated groove for 115 receiving opposite side edges of the top cover.

12. A wardrobe trunk, comprising hinged together trunk sections having adjacent edge portions, one of said sections having a hinged top cover, and coacting valance 125 members mounted on the edge and top cover portions, one of said valance members consisting of a strip of metal folded over in part upon itself medially of its width to 130

4
form overlapping portions, and then extending at right angles to form grooves for receiving edge portions of the trunk; another of said valance members consisting of a strip of metal folded over in part upon itself medially of its width to form a drawer holding portion, and then both side portions extending in spaced relation and at right angles to the stop portion to form an elongated groove for receiving edge portions of the trunk, and another of said valance mem-

bers formed of a strip of metal folded over medially of its width to form a downwardly extending overlapping flange having side portions extending at right angles in spaced relation to form an elongated groove for receiving opposite side edges of the top cover, some of said grooved portions having offset side walls.

In testimony whereof I affix my signature. 20

GEORGE HENRY WHEARY.
